WRENCH

Ernest C. Worden, East Norwalk, Conn., assignor
to The Billings & Spencer Company, a corpora-
tion of Connecticut

Application August 4, 1940, Serial No. 351,413

13 Claims. (Cl. 64—29)

My invention relates to wrenches.

It has among its objects to provide an improved wrench of the so-called torque type and including improved means for automatically limiting the possible tightening effect obtainable with the wrench. A further object of my invention is to provide such improved means utilizing fluid pressure and having improved controlling means therefor whereby when a predetermined torque is exceeded, the driving and 10 driven elements of the wrench are automatically disconnected. Still further objects of my invention are to provide improved mechanism for enabling a suitable liquid as, for example, oil, to be utilized to control the torque exerted by the 15 wrench, and to provide improved oil chambers and improved cooperating means controlling the flow therebetween whereby when during operation of the wrench a predetermined pressure on the oil in one of said chambers is exceeded, communication is established between said chambers in such manner as to equalize the pressures therein and disconnect the driving and driven parts of the wrench. Other objects of my invention are to provide such an improved wrench which is 20 of compact form and adapted to be readily and inexpensively embodied in a motor operated wrench in such manner as to enable improved results to be obtained as compared with other wrenches now upon the market. These and other objects and advantages of my improved construction will, however, hereinafter more fully appear.

In the accompanying drawing, I have shown for purposes of illustration one form which my invention may assume in practice.

In this drawing:

Figure 1 is a side elevation showing my improved wrench in use;

Fig. 2 is an enlarged plan view of the torque controlling element;

Fig. 3 is a vertical section on line 3—3 of Figure 2;

Fig. 4 is a partial section similar to Figure 3 but showing the parts in another position;

Fig. 5 is a view similar to Figure 4 but showing still another position of the parts;

Fig. 6 is a transverse section on line 6—6 of Figure 3;

Fig. 7 is a transverse sectional view on line 7—7 of Figure 3, and

Fig. 8 is a perspective view of the piston member.

In this illustrative construction, I have shown my improved wrench as including a usual reversible, electric motor operated actuator mechanism 55

1 of a usual construction and carrying an adapter 2 rotated thereby and operating to rotate my improved torque controlling element 3 which herein also rotates a turning member, or adapter, 5 4 acting upon a bolt head or nut, indicated at 5; the several elements cooperating in an improved manner and the element 3 being of an improved construction, all as hereinafter more fully described.

Referring more particularly to the element 3, note that the latter herein includes a liquid tight casing adapted to house a suitable fluid as, for example, oil, and comprising cooperating members 6 and 7. Of these, the member 6 forms a cylinder 8 in which a piston 9 is movable, while the member 7 is a cover member suitably fixed to one end of the member 6 and connected thereto as by screws 10. This member 7 also is provided with an axial bore or passage 11 therethrough in which the rod 12 of the piston 9 is longitudinally movable, while it will also be noted that the cover 7 is herein provided with oppositely extending flanges 13 surrounding the bore 11, and that the outer flange 13 carries a packing nut 14 for compressing a usual packing 15. Herein, the piston 9 also has flanges 16 and 17 of different depth on its opposite edges, the deeper flange 17 being toward the cover 7, while a coiled spring 18 acts upon the face of the piston within this flange and between this face and a spring abutment plate 19 pressed against the inside face of the cover 7, the piston 9 normally being pressed by the spring 18 into the position shown in Figure 3.

35 Disposed within the casing and cooperating with the piston therein is improved oil flow controlling mechanism. As shown, longitudinal ports 20 are also provided on opposite sides of the axis of the piston 9, and each of these ports is suitably recessed, as shown at 21, to receive a ball 22 adapted to close the port 20 and to be moved away therefrom to permit the oil housed in the casing to pass between spaces 23 and 24 on opposite sides of the piston 9. Herein, the balls 22 are normally pressed into port closing position by suitable springs, illustrated as plate springs 25 suitably fixed at 26 to the piston 9 and disposed in opposite directions around the axis of the latter, as shown in Figure 6. Here it will also be noted that a valve 27 extends axially through the piston rod 12 and is adapted to seat on a conical valve seat 29 in the opposite face of the piston 9 and communicating with the space 23, while controlling the flow of liquid through an axially disposed communicating chamber 30 and laterally

extending angularly disposed ports 31 opening into the space 24. Herein this valve 27 has a stem 32 which is suitably packed at 32a and extends coaxially in an axial recess 33 in the piston rod 12 wherein it is acted upon by a coiled spring 34 acting between an adjustable nut 35 threaded on the end of the stem 32, and a suitable washer in the opposite end of the chamber 33. Herein, this nut 35 is held against rotation in the chamber 33 by a key way 36, while a turning slot 32b is provided in the projecting end of the stem 32 to permit desired adjustment. 10

Operatively connected between the piston and casing are also improved means for effecting rotation of one from the other. Here the piston rod 12 is provided on its extremity with a turning portion or squared nut 37 projecting beyond the packing nut 14. Also, the casing member 6 is provided with a corresponding coaxially disposed and oppositely extending turning portion 20 or squared nut 38. It will also be observed that the piston 9 is provided with oppositely located and oppositely disposed angular cam members 39 on its face in the chamber 23, these members 39 herein being equally spaced from the ports 22 and arranged relative thereto as shown in Figure 8. The member 6 is herein also provided with a pair of cooperating oppositely disposed cam members 40 raised from the bottom of the cylinder and disposed therein so as to cooperate with the cams 39.

with the cams 39. In the operation of the device, when the sloping faces of the cams 40 engage the sloping faces of the cams 39 and the squared end 38 is rotated by the motor driven actuator 1 through the adapter 2, the other squared end 37 will obviously be rotated therewith, the parts then being in the relation shown in Figure 3 and the oil pressure in the space 24 acting to maintain these cam faces in engagement. When, however, a predetermined torque is exceeded, cams 39, 40 slip and pressure in the space 24 is built up sufficiently to cause oil to pass down through the ports 31 against the valve 27 and open the latter, permitting the oil to flow into the space 23 tending to equalize the pressure in the spaces 23, 24. As a result, the piston 9 is caused to move longitudinally in the cylinder toward the cover 7, while the cams 39 and 40 are thus automatically moved toward a nonengaging position as shown in Figure 4. When, however, the pressure equalizes, the valve 27 will close automatically, this occurring substantially as the cams 40 and 39 pass out of contact with one another angularly. When this last occurs, the spring 18 then also acts automatically to press the piston 9 away from the cover 7 and this movement of the piston automatically opens the ball valves 22 as shown in Figure 5, so that oil also flows through the ports 20 to bring the parts back into the position shown in Figure 3. Thus, the element 3 acts automatically through its cams and associated hydraulic mechanism, to disconnect the motor operated actuator mechanism 1 from the adapter 4 whenever a predetermined torque is exceeded, i. e. whenever the valve 27 moves off its seat against the tension of its spring, in such manner that all nuts set by the wrench will be set with the same torque. Here, of course, it will also be evident that the setting may be adjusted as desired by suitably increasing or decreasing the tension of the spring 34 through an adjustment of the stem 32 relative to the nut 35.

As a result of my improved construction, it is

made possible to utilize only a single piston element in such manner as markedly to simplify the structure and reduce the expense thereof while minimizing the amount of alignment necessary and the objectionable effects of end play of the piston which, in a multi-piston construction, would change the volume of the chambers. Further, in my improved construction, the spring 18 automatically and quickly resets the device so that it is always ready for use following disconnection of the drive. It will also be observed that in my improved construction the automatic release is obtainable in only one direction of operation of the device while the latter provides a positive drive in the opposite direction, the ends of the cams being adapted to abut to provide such a positive drive. Thus, by merely reversing the power driven actuator, it is made possible to enable the wrench to be used under diverse conditions markedly extending its field of possible usefulness. Attention is also directed to the fact that the unit 3 may be turned end for end without reversing operation and to the further fact that, if desired, it may also be rotated by hand, or by a flexible power connection rather than the actuator 1. These and other advantages of my improved construction will, however, be clearly apparent to those skilled in the art.

in the art.

While I have herein specifically described one embodiment which my invention may assume in practice, it will be understood that this form of the same has been shown for purposes of illustration, and that the invention may be modified and embodied in other forms without departing from its spirit or the scope of the appended claims.

What I claim as new and desire to secure by Letters Patent is:

Letters Patent is.

40 1. A torque controlling driving device for wrenches having oppositely directed driving and driven turning elements, a fluid tight casing carrying the same and having said elements at opposite ends of said casing and one of said elements fixed to said casing and the other rotatable therein, and operative driving connections between said elements including a piston dividing said casing into two compartments and fluid pressure controlled valve means on said piston 45 for controlling the flow of fluid between said compartments and releasing the driven element 50 for controlling the flow of fluid between said compartments and releasing the driven element from the driving element when a predetermined torque is exceeded.

2. A torque controlling driving device for wrenches including a fluid containing casing comprising cooperating casing members, one including a cylinder open at one end, and the other forming a closure for the open end of said cylinder, oppositely directed turning elements carried by said casing, one carried on the exterior of one casing member and the other turning element rotatably mounted in the other casing member and having a piston in said casing dividing said casing into two compartments, valve means on said piston controlling the flow of fluid between said compartments, spring means acting on one side of said piston, and cooperating detent means carried on the opposite side of said piston and on the wall of said casing confronting said opposite side of said piston.

70 side of said piston.

3. A torque controlling driving device for wrenches having oppositely directed turning elements, a fluid containing casing carrying said elements comprising cooperating casing members, 75 one including a cylinder and having one of said

turning elements on the exterior thereof, and the other closing said cylinder and having the other turning element rotatably mounted therein, said last mentioned turning element carrying a piston in said cylinder dividing said casing into two compartments, valve means on said piston controlling the flow of fluid between said compartments, spring means acting on one side of said piston, and cooperating lug means between the opposite side of said piston and one of said casing members, said lug means having cooperating sloping engaging surfaces engageable in one relation of the parts to transmit power from one turning member to the other.

4. A torque controlling driving device for wrenches having oppositely directed turning elements, a fluid containing casing carrying said elements comprising cooperating casing members, one including a cylinder and having one of said turning elements on the exterior thereof, and the other closing said cylinder and having the other turning element rotatably mounted therein, said last mentioned turning element carrying a piston in said cylinder dividing said casing into two compartments, valve means on said piston controlling the flow of fluid between said compartments, spring means acting on one side of said piston, and cooperating lug means between the opposite side of said piston and one of said casing members, said lug means having cooperating sloping engaging surfaces engageable in one relation of the parts to transmit power from one turning member to the other and cooperating shoulders engageable in another relation of the parts to effect a positive drive upon reverse rotation of one of said turning elements.

5. A torque controlling driving device for wrenches having oppositely directed turning elements, a casing carrying the same having one of said elements fixed thereto and the other rotatable therein, and operative driving connections between said elements including fluid pressure controlled means in said casing releasing the driven element from the driving element when a predetermined torque is exceeded and having a piston and cylinder carried by different turning members and cooperating driving cams in said cylinder, one of which is on said piston.

6. A torque controlling driving device for wrenches having oppositely directed turning elements, a casing carrying the same having one of said elements fixed thereto and the other rotatable therein, operative driving connections between said elements including fluid pressure controlled means in said casing releasing the driven element from the driving element when a predetermined torque is exceeded and having a piston and cylinder carried by different turning members, spring means in said casing biasing said piston to one end of said cylinder, and cooperating driving cams on said piston and on said end of said cylinder having sloping surfaces normally pressed into engagement by said spring means.

7. A torque controlling driving device for wrenches having oppositely directed turning elements, a casing carrying the same having one of said elements fixed thereto and the other rotatable therein, and operative driving connections between said elements including fluid pressure controlled means in said casing releasing the driven element from the driving element when a predetermined torque is exceeded, and having a piston carried by one turning element and movable in a cylinder carried by the other, and pres-

sure controlling valve mechanism carried by said piston and operative to equalize the pressures on opposite sides of said piston when a predetermined torque is exceeded.

5 8. A torque controlling driving device for wrenches having oppositely directed turning elements, a casing carrying the same having one of said elements fixed thereto and the other rotatable therein, and operative driving connections between said elements including fluid pressure controlled means in said casing releasing the driven element from the driving element when a predetermined torque is exceeded, and having a piston carried by one turning element and movable in a cylinder carried by the other, and pressure controlling valve mechanism carried by said piston and operative to equalize the pressures on opposite sides of said piston when a predetermined torque is exceeded, and including an axially located spring pressed valve controlling the communication between opposite sides of the piston and having adjusting means adjustable from the projecting end of the piston rod.

15 9. A torque controlling driving device for wrenches having oppositely directed turning elements, a casing carrying the same having one of said elements fixed thereto and the other rotatable therein, operative driving connections between said elements including fluid pressure controlled means in said casing releasing the driven element from the driving element when a predetermined torque is exceeded and having a piston carried by one turning element and movable in a cylinder carried by the other, and pressure controlling valve mechanism carried by said piston and operative to equalize the pressures on opposite sides of said piston when a predetermined torque is exceeded, said valve means including an axially located spring pressed valve controlling the communication between opposite sides of the piston and having adjusting means adjustable from the projecting end of the piston rod, and cooperating spring pressed valves carried on the body of the piston and also controlling the communication between the opposite sides thereof.

20 10. A torque controlling driving device for wrenches having oppositely directed turning elements, a casing carrying the same having one of said elements fixed thereto and the other rotatable therein, operative driving connections between said elements including fluid pressure controlled means in said casing releasing the driven element from the driving element when a predetermined torque is exceeded and having a piston carried by one turning element and movable in a cylinder carried by the other, pressure controlling valve mechanism carried by said piston and operative to equalize the pressures on opposite sides of said piston when a predetermined torque is exceeded, said valve means including an axially located spring pressed valve controlling the communication between opposite sides of the piston and having adjusting means adjustable from the projecting end of the piston rod, cooperating spring pressed valves carried on the body of the piston and also controlling the communication between the opposite sides thereof, and spring means normally urging said piston to one end of said cylinder.

25 11. A torque controlling driving device for wrenches including a fluid containing casing comprising cooperating casing members, one including a cylinder open at one end and the other closing the open end of said cylinder, oppositely directed turning elements carried by said casing,

one on the exterior of one casing member and the other turning element rotatably mounted in the other casing member and having a piston in said cylinder dividing said cylinder into fluid containing compartments, spring means acting on one side of said piston, cooperating lug means between the opposite sides of said piston and one of said casing members, and port and valve means carried by said piston controlling the pressure flow of fluid between opposite sides of the latter.

12. A torque controlling driving device for wrenches including a fluid containing casing comprising cooperating casing members, one including a cylinder open at one end and the other closing the open end of said cylinder, oppositely directed turning elements carried by said casing, one on the exterior of one casing member and the other turning element rotatably mounted in the other casing member and having a piston in said cylinder dividing said cylinder into fluid containing compartments, spring means acting on one side of said piston, cooperating lug means between the opposite sides of said piston and one of said casing members, and port and valve means carried by said piston controlling the pressure

flow of fluid between opposite sides of the latter, including oppositely movable valves carried by said piston.

13. A torque controlling driving device for wrenches having oppositely directed turning elements, a fluid containing casing carrying said elements comprising cooperating casing members, one including a cylinder having one of said turning elements on the exterior thereof, and the other closing said cylinder and having the other turning element rotatably mounted therein, said last mentioned turning element carrying a piston in said cylinder dividing said cylinder into fluid containing compartments, spring means acting on one side of said piston, cooperating lug means between the opposite sides of said piston and one of said casing members, and port and valve means carried by said piston controlling the pressure flow of fluid between opposite sides of the latter including oppositely movable valves carried by said piston and one being axially disposed and having adjusting means adjustable from the end of the piston rod and the other comprising spring pressed ball valves carried by the body of the piston.

ERNEST C. WORDEN.
